US0D1075685S

(12) **United States Design Patent** (10) **Patent No.:** **US D1,075,685 S**
(45) **Date of Patent:** **** May 20, 2025**

(54) **OUTLET AND REMOTE CONTROL ASSEMBLY**

(71) Applicant: **Xiaomin Guo**, Shenzhen (CN)

(72) Inventor: **Xiaomin Guo**, Shenzhen (CN)

(**) Term: **15 Years**

(21) Appl. No.: **29/974,942**

(22) Filed: **Nov. 26, 2024**

(51) LOC (15) Cl. **13-03**

(52) U.S. Cl.

USPC **D13/137.2**; D13/168

(58) **Field of Classification Search**

(57) **CLAIM**

The ornamental design for an outlet and remote control assembly, as shown and described.

DESCRIPTION

FIG. 1 is a front, right and top perspective view of an outlet and remote control assembly, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

(Continued)

The broken lines shown in the drawings illustrate portions of the outlet and remote control assembly that form no part of the claimed design.

1 Claim, 8 Drawing Sheets
